UNITED STATES PATENT OFFICE.

HENRY ANDREW MEYER, OF CINCINNATI, OHIO, ASSIGNOR TO THE WOLF MACHINE COMPANY, OF CINCINNATI, OHIO, A CORPORATION OF OHIO.

MEAT SAW.

Application filed March 23, 1925. Serial No. 17,678.

To all whom it may concern:

Be it known that I, HENRY A. MEYER, a citizen of the United States, residing at Cincinnati, in the State of Ohio, have invented certain new and useful Improvements in Meat Saws, of which the following is a specification.

This invention relates to power-driven saws for making the scribe cut in dressed pork and like purposes and has special reference to the shield and gage, the object being to provide a shield and gage which may be easily set in a desired position and be effectually held in the set position without likelihood of being accidentally released. The invention is illustrated in the accompanying drawing and will be hereinafter fully set forth and defined.

In the annexed drawing:

20 Figure 1, is a front elevation of a meat saw having the present invention applied thereto;

25 Figure 2, is an enlarged end elevation of the same, the motor casing being omitted; and

Figure 3, is an enlarged horizontal section on the line 3—3 of Figure 1.

In the drawing, the reference numeral 1 denotes a motor casing in which an electric or other motor may be housed and which is equipped with handles 2 and 3 whereby it may be held and guided while at work. Secured to and depending from this casing is a hollow stem 4 carrying a frame plate and housing a spindle or shaft 6 forming a part of the gearing whereby motion is imparted to the saw 7. The frame plate 5 is inset relative to the stem 4 and is of such form that it constitutes a shield partly housing the saw which lies close to the outer face of the plate but extends below the same as shown in Figure 2. Pivoted, as at 8, to a flange of the frame plate 5 is an adjustable shield or gage 9 which is provided centrally with an opening 10 to accommodate the nut or collar 11, which holds the saw upon its arbor, whereby the gage may be disposed close to the saw. At its free edge, the gage is provided with an arcuate slot 12 through which a stop screw 13 is inserted into the adjacent flange of the frame plate, the slot being concentric with the pivot and the engagement of its end walls with the stud or screw 13 limiting the pivotal adjustment of the gage. To effect adjustment of the gage

a lever or handle 14 is pivoted at one end to a lug 15 on the gage and extends therefrom across and beyond the gage. Secured to the frame plate adjacent the free edge of the gage is a keeper bracket 16 having a plurality of notches 17 in its front vertical edge in any one of which the adjusting lever or handle may be engaged. A leaf spring 18 is secured upon the lever at the pivoted end thereof and extends beyond the same to bear at its free end against the gage and thereby hold the lever toward the keeper bracket and within the notch 17 in which it may be set. A guiding loop bracket 19 is secured upon the gage and spans the lever, as shown, whereby the pivotal movement of the lever outwardly from the plate is limited and the vertical movement of the lever is imparted to the gage with minimum strain upon the lug 15.

It will be evident that tightening of the screw 13 will hold the gauge in its adjusting position, and that either screw 13, or spring 18, or both, may be used for this purpose as occasion demands.

Obviously, the saw is so housed between the frame plate and the gage that the liability of the user having injurious contact therewith is practically eliminated, and the depth of the cut is determined by setting the gage at a higher or lower point. To set the gage, the lever is released from the bracket 16 and swung upwardly or downwardly to the proper point and then reengaged with the keeper bracket.

The arrangement is very simple and compact and of such construction that the liability of some part wearing loose to prematurely or accidentally release the lever and gage is negligible.

Having described my invention, what I claim as new and desire to secure by Letters Patent, is:

A device of the class described comprising a casing for a motor, a housing depending from said casing and mounting a shaft secured to the motor shaft, said housing having a part thereof projecting downwardly and provided with a bearing, a shaft mounted in said bearing, a rotary saw mounted on said shaft to rotate therewith, said housing and projecting part being recessed and widened to receive and project laterally to the front and rear of the saw and to provide a guard for one side thereof,

lying closely adjacent thereto and beyond which only a small portion of the saw projects, a combined gauge and guard for the other side of the saw adjustably secured to
5 said projecting part, a handle on the gauge rigid therewith in its plane of motion for setting same and having a lateral movement

into and out of engagement with means on the projecting part of the housing within the width of its widened portion to hold the 10 gauge in a set position.

In testimony whereof I hereunto affix my signature.

HENRY ANDREW MEYER.
